GRINDING MACHINE

Frederick S. Haas, Cincinnati, Ohio, assignor to
 Cincinnati Grinders Incorporated, Cincinnati,
 Ohio, a corporation of Ohio

Application November 1, 1929, Serial No. 404,113

6 Claims. (Cl. 51—103)

This invention relates to improvements in grinding machinery and has particular reference to an improved mechanism for use in grinding both the periphery and adjacent face or shoulder portion of work pieces having more than a single diameter.

One of the principal objects of the present invention is the provision of an improved controllable mechanism which may be utilized for either traverse or direct infeed or plunge cut type of grinding and in which the same grinding wheel may be employed for shaping the periphery of a rotary work piece for example and may also be utilized for cleaning up the face or shoulder of a projecting portion of the same work piece.

An additional object of the present invention is the provision of an improved mounting for a grinding wheel spindle and control mechanism for effecting a desired reciprocating or shifting movement of the spindle with respect to its associated bearings.

An additional object of the present invention is the provision in connection with grinding mechanism as aforesaid employed either in a center or centerless type grinding of an improved associated mechanism for formation of the operative face on the grinding member.

Other objects and advantages of the present invention should be readily apparent by reference to the following specification considered in conjunction with the accompanying drawings forming a part thereof and it will be understood that I may make any modifications in the structural details hereinafter disclosed within the scope of the appended drawings without departing from or exceeding the spirit of the invention.

Figure 1 is a front elevation of one form of grinder embodying the improvements forming the subject matter of the present invention.

Figure 2 is a plan view thereof.

Figure 3 is a longitudinal section through the grinding wheel spindle and face truing mechanism therefor as on the line 3—3 of Figure 2.

Figure 4 is a fragmentary horizontal section illustrating the control cam as on line 4—4 of Figure 3.

Figure 5 is a transverse section through the truing mechanism aforesaid.

In the drawings in which similar characters of reference are used to denote corresponding parts throughout the several views the numeral 10 designates the bed of a machine of the general centerless grinding type having supported at one end thereof the wheel guard housing 11 circum-

scribing the grinding wheel 12. This wheel is secured on a spindle 13 journaled in bearings 14 of the wheel head 15. This wheel head is slidably mounted on the bed 10 and adapted to be variably adjusted with respect thereto as by feed screw 16. Disposed on the bed in opposition to the grinding wheel is a slide 17 bearing the work rest bracket 18 and a supplemental slide 19 for the regulating wheel unit 20. This unit 20 has pivoted thereto the guard housing 21 within which is journaled regulating wheel 22 located in opposition to the grinding wheel and adapted to have its axis tilted with respect to that of the grinding wheel in such manner as to create a feed component urging the work inwardly toward the machine as viewed in Figures 1 and 2. The work piece proper comprises a member having a cylindrical portion 23 supported by the work rest blade 24 carried by bracket 18, and having an over-hanging head or plate portion at 25. The present invention is utilizable either in connection with a centerless grinder such as illustrated or alternatively with a center type grinding machine in which a different mechanism is utilized for supporting and rotating the work piece while maintaining it against undesired longitudinal or axial movement. In the present instance the tilt of the regulating wheel exerts a feed component on the work holding the work toward the stop or end movement limiting member 26 suitably associated with the work rest bracket or bed portion of the machine. This action holds the work against endwise movement in the machine during grinding.

It will be noted that the particular work piece shown has a small cylindrical portion disposed in the grinding throat with an enlargement or head 25 at the forward end. It is therefore, preferable that suitable steadyng means such as the shoe 27 be utilized for preventing chatter or tilt of the work on its support.

In the operation of the machine the work and grinding wheel are given a suitable feeding movement one toward the other to cause the periphery of the grinding wheel to suitably grind the cylindrical body portion 23 of the work. In addition it is desired that the inner face of the head or shoulder of the work be given a suitable face grinding.

To facilitate performance of this operation the spindle 13 supporting the grinding wheel 12 is mounted for both rotation and axial sliding or reciprocating movement within the bearings 14. The spindle is further formed with a reduced terminal portion as at 28 on which is seated the

anti-friction bearing ring 29 for the ball or similar anti-friction bearings 30, outwardly engaging the washer 31 mounted on the shouldered terminal portion of the spindle. The spindle has 5 a threaded extension 32 beyond the shoulder for engagement with the elongated nut member 33 which serves to properly clamp the washer in place and retain the bearing as an entirety against outward displacement. Circumscribing 10 this unit 33 is a second bearing ring 34 while interposed between the ring and washer are a second set of anti-friction bearings 35.

Circumscribing nut 33 is a sleeve 36 slidably mounted in the interior of a second circumscribing sleeve 37 having an interned flange or rib 38 loosely surrounding the reduced terminal portion 28 of the spindle and inwardly engaging the washer 39 forming a part of the general inner anti-friction bearing on the spindle.

20 Exterioly the sleeve 37 has a reduced portion as at 40 receiving a spring 41 which bears at one end against the abutment 42 set in a recess 43 in the member 15 and bearing at its opposite end against shoulder 44 of the sleeve. It will be noted that this is a heavy coil spring and on account of the arrangement described tends to press the spindle outward or to the right as viewed in Figure 3. On account of the interposition of the anti-friction bearing members 30 the spindle will rotate freely irrespective of any pressure thereagainst. The journal 15 is provided with a tubular extension 45 within which the sleeve member 37 slides, this member having a shoulder as at 46 which will positively limit the outward movement of the sleeve and thus of the bearing associated therewith.

40 The outward movement however is further variably limited by means of a rock shaft 47 carried by the extension 45 and bearing a cam member 48 having a flat face as at 49 normally, terminally engaging plug 50 in the end of sleeve 36 as shown in Figure 4.

45 On oscillation of shaft 47 through the medium of handle 51 the cam will be turned causing the eccentric rounded face 52 thereof to bear against the plug camming the spindle inwardly or toward the left and thus causing a movement of the grinding wheel in that direction. This movement of the grinding wheel is readily controllable by the handle and may be effected in sufficient amount to cause the face 53 of the grinding wheel to engage and properly to abrade the shoulder or head at the terminus of the portion 23 of the work piece previously ground.

55 It will be noted that the thrust component exerted by the regulating wheel is sufficient to maintain the work piece against axial or outward movement during pressure of the grinding wheel there-against.

60 The eccentricity of the portion 52 of the cam is such as to permit of considerable longitudinal or axial movement of the grinding wheel shaft and in fact a movement considerable in excess of that necessary for the ordinary performance 65 of the grinding operation with the result that in a normal setting of the parts a considerable wearing away of the front face of the grinding wheel is permissible before relative transverse readjustment of the grinding wheel and work supporting member is necessary. However, in the event that the face of the grinding wheel, due to wear or truing has been unduly removed, the parts may be given this relative adjustment as for example by a shifting of the member 15 on its support 10 as previously referred to.

It will be understood that machines of the general nature here disclosed are intended for precision grinding operations with the result that the wheel surface must be as near perfect as possible and maintained in a free cutting condition. To attain this result the housing 11 shown as provided with suitable truing mechanisms for operation respectively on the face and the periphery of the grinding wheel. The mechanism for truing or preserving the operative peripheral 10 surface of the grinding wheel includes a bracket 55 carried by the housing 11 and supporting a transversely movable slide 56 actuatable by hand wheel 57 and screw 58 to traverse the face of the wheel. Slide 56 bears the longitudinal adjustable plunger 59 having at one end the truing diamond 60, and at the other engaged by the adjusting screw 61 for determining its inward effective position.

20 In addition the housing bears a second bracket 20 member 62 in which is slidably mounted a plunger 63 suitably keyed or held against rotative movement and bearing at its lower end a slide block 64 adjustable by screw 65 for determining the position of the diamond 66. Plunger member 63 25 is formed with a rack 67 meshing with pinion 68 rotatable by hand wheel 69. With the spindle held to the right by pressure of the spring 41 the diamond is moved in or out as is necessary by adjustment of screw 65 and block 64 to just engage 30 with the face of the grinding wheel. Rotation of wheel 69 then causes an up and down or radial movement of the diamond with respect to the face of the wheel properly truing off same for said operation on the shoulder or head of the work 35 piece so that this face of work circumscribing the ground cylindrical portion thereof will be produced absolutely, normal to the axis of the body of the work.

40 From the foregoing description the construction and operation of the present improved grinding machine should be readily understood and it will be noted there has been provided a machine in which there are means for supporting and rotating a shouldered or other work piece, for restricting axial movement of the work piece during grinding and for facilitating the performance of simultaneous or successive grinding operations on the body and the adjacent shoulder of the work piece, together with means for establishing and maintaining the operative lateral and peripheral faces of the grinding wheel in satisfactory condition for grinding the respective parts referred to and with a sharp or substantially non-filletted corner at the intersection 50 of the two surfaces and a machine which will produce these surfaces at absolute right angles 55 one to the other.

60 In a more specific aspect it will be noted that a mechanism has been provided of a type in which the work being supported on a work rest between grinding and regulating wheels will definitely establish its axis and be produced to true cylindrical form and which by a subsequent slight shifting or manipulation of certain portions of the 65 machine a second surface may be formed and produced on the work in definite and predetermined relation to a previously preformed surface without the necessity for duplicate handling of the parts transferred from one machine to the 70 other or the like.

I claim:—

1. A centerless grinder for operation on a work piece having a peripheral portion and a lateral face portion to be ground comprising a bed, a pair 75

of opposed grinding and regulating wheels carried thereby and forming a grinding throat therebetween, the grinding wheel having a peripheral abrasive face and a lateral abrasive face,

- 5 means within the grinding throat for supporting the work piece for rotation, a housing for the regulating wheel, means pivotally supporting the housing whereby the regulating wheel may be tilted to exert an axial feeding component on the
 10 work piece, a stop limiting the axial movement of the work piece, a spindle for the grinding wheel, a support therefor, and means for axially shifting the spindle and grinding wheel to operatively relate the lateral abrasive face of the grinding
 15 wheel and the lateral portion of the work piece to be ground.

2. A centerless grinder for operation on a work piece having a peripheral portion and a lateral face portion to be ground comprising a bed, a pair of opposed grinding and regulating wheels carried thereby and forming a grinding throat therebetween, the grinding wheel having a peripheral abrasive face and a lateral abrasive face, means within the grinding throat for supporting the work piece for rotation, a housing for the regulating wheel, means pivotally supporting the housing whereby the regulating wheel may be tilted to exert an axial feeding component on the work piece, a stop limiting the axial movement of the work piece, a spindle for the grinding wheel, a support therefor, means for axially shifting the spindle and grinding wheel to operatively relate the lateral abrasive face of the grinding wheel and the lateral portion of the work piece to be ground, said means including a manually operable cam for shifting the spindle in one direction and a yieldable means for shifting the spindle in the other direction.

3. A centerless grinder for operation on a work piece having a plain portion and a lateral portion to be ground comprising a bed, a pair of opposed grinding and regulating wheels carried thereby and forming a grinding throat therebetween, the grinding wheel having a peripheral abrasive face and a lateral abrasive face, means within the grinding throat for supporting the work piece for rotation, a housing for the regulating wheel, means pivotally supporting the housing whereby the regulating wheel may be tilted to exert an axial feeding component on the work piece, a stop

limiting the axial movement of the work piece, a spindle for the grinding wheel, a housing, bearing carried by the housing for the spindle, the grinding wheel, spindle, housing and bearings constituting a grinding wheel unit, means for shifting the grinding wheel unit transversely of the bed in the direction of the spindle axis and additional means for axially shifting the spindle independently of the housing and bearings.

4. A grinding machine comprising a bed, a work support on the bed, means restricting axial movement of the work on the support during grinding, a wheel head supported by the bed, a spindle journaled in the head, a grinding wheel supported by the spindle, means for shifting the head and supported parts as a unit relative to the bed in the direction of the longitudinal axis of the spindle, means for additionally axially shifting the spindle and grinding wheel independently of the head, said means including a manually actuatable cam for shifting the spindle in one direction, and yieldable means for shifting the spindle in the opposite direction.

5. In a centerless grinder the combination of a pair of opposed grinding and regulating wheels forming a grinding throat therebetween, a work support subtending the grinding throat, a wheel head for each of the wheels, a spindle for each wheel rotatably supported by the wheel heads, means for adjusting one of the wheel heads in a direction axially of its spindle, and additional means for axially adjusting the spindle independently of the movement imparted thereto by the wheel head.

6. In a centerless grinder the combination of a pair of opposed grinding and regulating wheels forming a grinding throat therebetween, a work support subtending the grinding throat, a wheel head for each of the wheels, a spindle for each wheel rotatably supported by the wheel heads, means for adjusting one of the wheel heads in a direction axially of its spindle, additional means for axially adjusting the spindle independently of the movement imparted thereto by the wheel head, said means including a cam carried by the wheel head for movement therewith and independently thereof, a lever for actuating the cam, and spring means for maintaining contact between the spindle and cam.

FREDERICK S. HAAS. 50
